D. HATHAWAY.

Stove Grate.

No. 98,059

Patented Dec. 21, 1869.

INVENTOR.

David Hathaway

United States Patent Office.

DAVID HATHAWAY, OF TROY, NEW YORK.

Letters Patent No. 98,059, dated December 21, 1869.

STOVE-GRAVE.

The Schedule referred to in these Letters Patent and making part of the same.

To all whom it may concern:

Be it known that I, DAVID HATHAWAY, of the city of Troy, in the county of Rensselaer, and State of New York, have invented a new and improved Stove-Grate; and I do hereby declare that the following is a full, clear, and exact description of the same, reference being hereby had to the accompanying drawings, which form and make a part of this, my specification.

The nature of my invention consists in so arranging the sliding bars, which form the bed of the grate, that they may part longitudinally in the centre, their outer edges revolving on journals, supported by loops attached to the bed-plate or stationary frame, their inner edges dropping down into the ash-pit, leaving a clear passage between said bars for the discharge of exhausted fuel. These bars are again turned into position, (having their upper surfaces in the same horizontal plane, even with the under side of the bed-plate, and passing under the same,) by means of a swinging clasp, approaching in form a semicircle, having journals at the ends revolving in loops in the bed-plate, the axes of said journals being at right angles, transversely, across the bed-plate and sliding bars.

The inner edges of these bars are supported near the centre by said clasp, and have a sliding motion thereon.

In the annexed drawing—

A, Figure 1, represents the bed-plate, which may be placed in the fire-chamber of stoves, ranges, &c., and secured in a horizontal position in the usual manner.

B and C are the sliding bars, which constitute the bed of the grate, upon which fuel is to be placed.

These bars have, on their outer edges, at each end, the journals marked, respectively, D E F G.

The journals D and E (fig. 1) are supported by, revolve, and slide in the loops N and O, attached to the bed-plate, the ends of the journals passing under the bed-plate far enough to prevent their being thrown out of the loops.

Figure 4 represents a part of the under side of the grate.

The journals F and G are supported by and revolve on the ends of the yoke H, which is movable on the pivot K, which is attached to the bed-plate.

These journals slide between and are retained in their proper lateral position by the nibs marked x x.

Figures 5 and 6 indicate more clearly the connection of the journals F and G with the ends of the yoke H.

Figure 3 is a vertical transverse section, showing the position of the sliding bars and swinging clasp, when the grate is in its dumped position.

Figure 2 is the swinging clasp, (partially seen in

fig. 1,) which actuates the sliding bars in the operation of dumping and replacing the grate.

Attached to this clasp, at right angles to its plane and the axes of its journals U and V, is the arm S.

Connected with this arm, by means of the pivot Y, (fig. 1,) is the rod T, which has a sliding motion (in the operation of dumping) in the loop J, and is locked therein by means of a notch near the end of the rod, as at P.

When the rod is in this position, the clasp is pressed up against the inner under edges of the sliding bars, holding them in a horizontal position, nearly touching the under side of the bed-plate, leaving sufficient room for the bars to slide freely.

When the grate is in this position, (as indicated by fig. 1,) the weight of the sliding bars resting upon the clasp, and acting through the arm S, forces the rod T in the direction of its length, pressing the notch P firmly against the loop J. In this position the plane of the clasp is parallel with the plane of the bed-plate.

The grate is dumped by raising the rod T from its lock in the loop J; the rod will take the position indicated by the broken lines; the clasp will revolve on its journals U and V, in the loops M and R, its plane taking nearly a vertical position, the inner edges of the sliding bars dropping down into the ash-pit, as indicated by fig. 3.

The grate is replaced by pressing the rod T in the direction of its length, so that the notch P will lock into the loop J.

In order to shake the grate, for the purpose of sifting ashes from the fuel, place the wrench, Figure 7, into the yoke H, figs. 1 and 4, and move it to the right and left, as indicated by the broken curved line, fig. 7.

This operation communicates an oscillating motion to the yoke H, which turns on the pivot K; and the ends of the yoke being connected with the journals F and G, of the sliding bars B and C, motion is given to said bars in the direction of their length.

In this arrangement for a stove-grate,

What I claim as my invention, is—

1. The central sliding bars B C, the outer edges of which revolve on the journals D E and F G, the inner edges dropping down into the ash-pit, leaving a wide opening between said bars, constructed, arranged, and operating as set forth.

2. The clasp, fig. 2, in combination with the rod T and arm S, by which the grate is dumped, and the sliding bars again replaced in working position, substantially as described.

Witnesses: DAVID HATHAWAY.
